CIRCUIT BREAKER

Hiller D. Dorfman, Forest Hills, and Gerald J. Freese, East McKeesport, Pa., assignors to Westinghouse Electric & Manufacturing Company, East Pittsburgh, Pa., a corporation of Pennsylvania

Application June 24, 1941, Serial No. 399,456

12 Claims. (Cl. 200—67)

This invention relates to circuit breakers, and more particularly to circuit breakers of the type which are manually operable to open or to close the circuit and automatically operable to open the circuit upon the occurrence of an overload condition or short circuit.

One object of the invention is to provide a circuit breaker having improved means to cause quick opening and closing of the contacts.

Another object of the invention is to provide a circuit breaker having improved means for causing the contacts to open a greater distance without increasing the size of the operating mechanism.

Another object of the invention is to provide a circuit breaker with improved means to prevent vibration or chatter of the contacts when they are opened or closed.

Another object of the invention is to provide a circuit breaker with improved means for applying contact pressure to the contacts when said contacts are closed.

Another object of the invention is the provision of a circuit breaker having improved circuit opening and closing characteristics, and which is simple in construction and inexpensive to manufacture.

Another object of the invention is to provide a circuit breaker having a contact arm pivoted on a movable switch member and a toggle for operating the contact arm to cause a greater separation of the contacts than if the contacts were mounted in the usual way on the switch member.

Another object of the invention is to provide a circuit breaker with means for increasing the contact pressure as the contacts start to open.

Another object of the invention is to provide a circuit breaker with novel means whereby the pressure applied to the contacts increases as the contacts wear.

A further object of the invention is to provide a circuit breaker with improved means to cause the contacts to open and close with a wiping action.

The novel features that are considered characteristic of the invention are set forth in particular in the appended claims; the invention itself, however, both as to structure and operation, together with additional objects and advantages thereof, will be best understood from the following detailed description of several embodiments thereof when read in conjunction with the accompanying drawings, in which:

Figure 1 is a front elevational view of a three- 55

pole circuit breaker embodying the principal elements of the invention. The cover has been partly broken away to more clearly show some of the parts of the breaker.

Fig. 2 is a vertical sectional view of the circuit breaker taken substantially on line II—II of Fig. 1 and looking in the direction of the arrows, the breaker being shown in closed circuit position.

Fig. 3 is a vertical sectional view of the circuit breaker similar to Fig. 2, but showing the breaker in its tripped open position.

Fig. 4 is an enlarged detail view of a modification of the movable contact arm, said arm being shown in closed contact position by the full lines and in its fully open position by the dot and dash lines.

Referring to Figs. 1 and 2 of the drawings, the circuit breaker includes a base 11 of molded insulating material on which the several elements of the breaker mechanism are mounted. A cover 12 also of molded insulating material is removably secured to the base and cooperates therewith to form an enclosing housing for the parts of the circuit breaker.

The circuit breaker is of the multi-pole type, each pole comprising a pair of terminals 13 and 15, one mounted at each end of the base, a stationary contact 17, an arc extinguisher 19 and a movable contact 21. A common operating mechanism indicated generally at 22 is provided for simultaneously actuating the three movable contacts 21, and a three pole trip device 23 serves to effect automatic opening of the three movable contacts 21 in response to predetermined overload conditions in the circuit through any pole of the breaker.

Each of the movable contacts 21 is mounted on a contact arm 25 pivotally supported intermediate its ends on a pivot pin 26 in the free ends of a pair of switch arms 27. The arms 27 are mounted on a rectangular tie bar 29 of insulating material and are joined by a rectangular sleeve 31 surrounding the tie bar and secured thereto so that all of the arms 27 move as a unit. A flexible shunt conductor 33 connects the contact arm 25 with an angular terminal 32 secured by a screw 33 to one end of a conductor 35. The other end of the conductor 35 is connected by a flexible shunt conductor 37 to a point near the free end of a bimetal element 38, said bimetal element being rigidly secured on the inner end of a conductor 41. The terminal 15 is secured to the outer end of the conductor 41. Each of the stationary contacts 17 is mounted on the inner end

of a conductor 43 having its outer end connected to a corresponding terminal 13.

The electrical circuit for each of the poles is essentially the same and extends from the terminal 13 through the conductor 43, stationary contact 11, the movable contact 21, the contact arm 25, the flexible shunt conductor 30, the terminal 32, the conductor 35, the flexible shunt conductor 37, the bimetal element 39 and the conductor 41 to the terminal 15.

In order to prevent flashovers between the poles of the breaker, barriers 42 (Figs. 1 and 2) are molded integral with the base 11 and extend the length of the breaker. When the cover 12 is in place, barriers 45 (Fig. 2) molded integral with said cover are in alignment with the barriers 42 and form separate compartments for the poles. The tie bar 29 is provided with annular projections 48 which fit within recesses 50 in the barriers 42 to close the openings in the barriers through which the tie bar extends.

The operating mechanism for the breaker indicated generally at 22 (Fig. 2) is supported on a frame comprising a pair of frame members 44 inserted in slots in the barriers 42 and suitably secured to the center part of the base 11. The operating mechanism includes a forked operating lever 47, toggle links 49 and 51, a pair of overcenter springs 53 and a releasable cradle 55 controlled by the trip device 23. The springs 53 are tensioned between a clip 54 on the toggle knee pin 65 and the lever 47. The cradle 55 is pivotally supported on the frames 44 by a pivot pin 56 extending between frames. The inner ends of the forks of the operating lever 47 are rounded and are pivotally seated in pivot bearing recesses in the frame 44 as indicated at 57, the slots in the barriers 42 which receive the forks of the lever 47 acting as guides to prevent lateral displacement of the forks. An insulating shield 59 for covering an opening 61 in the cover 12 is mounted on the outer end of operating lever 47. A manual operating handle 63 integral with the shield 59 projects through the opening 61 to permit manual operation of the breaker mechanism.

The toggle links 49 and 51 are pivotally connected by a knee pin 65. The link 51 is pivotally connected by a pivot pin 67 to the arms 27 which carry the contact arm 25 for the center pole and the link 49 is bifurcated at its outer end and pivotally engages a pin 69 on the cradle 55 being retained in engagement therewith by the overcenter springs 53 tensioned between the knee pin 65 and the outer portion of the operating lever 47. The overcenter movement of the toggle 49-51 is limited by a stud 66 on the link 51 just below the knee pin 65 striking a projection 68 on the cradle 55. This projection 68 also acts to positively start the toggle in a direction to cause collapse thereof when the breaker is tripped automatically in response to an overload as will be described later.

The arms 27 which pivotally carry the contact arms 25 for all three poles are mounted on the insulating tie bar 29 so that the contacts for all poles are operated simultaneously, and yet each pole is insulated from the other poles. An axially disposed metal shaft 71 extends through the tie bar 29 and rotatably supports the tie bar in brackets 13 suitably secured to the base 11 of the breaker.

Overcenter springs 77 are associated with the contact arms 25. These springs surround contact arm operating members 79 and are compressed between angular brackets 81 secured to

the pivoted ends of the switch arms 27 and shoulders 83 on the members 79. The springs 77 hold the ends of the members 79 in engagement with recesses 85 in the inner ends of the contact arms 25. The brackets 81 serve to support and guide the members 79, the members 79 extending through enlarged guide openings in the brackets 81. Each contact arm 25 and its cooperating toggle member 79 forms a snap action toggle which, in the closed circuit position, is overcentered in a direction which permits the spring 77 to apply pressure to the contacts.

As previously stated, the trip device 23 includes a bimetal 39 connected in series in the circuit for each pole of the breaker. The trip device also includes a trip bar 87 of molded insulating material pivotally supported in bearings in the side walls of the breaker base.

Each pole of the breaker is provided with a latch lever 93 pivotally supported on a U-shaped frame 95 by a pivot pin 97, the frame 95 being mounted on the base 11. A spring 105 compressed between a bar 107, supported between the legs of the frame, and the latch lever 93, biases said lever in a clockwise direction. Clockwise rotation of the latch lever 93 is normally prevented by engagement of its latch end with a latch 109 on the free end of the bimetal 39.

A latch member 111 secured to projections 113 molded integral with the trip bar 87 normally engages the latch end of the cradle 55 and thereby restrains the cradle 55 in its operative position.

When any one of the bimetal elements 39 is heated a predetermined amount in response to an overload current, it flexes in a direction to unlatch its corresponding lever 93 whereupon the spring 105 rocks the lever 93 in a clockwise direction. During this movement the end of the lever 93 strikes a projection 115 on the trip bar 87 and rocks said trip bar counterclockwise causing the latch member 111 to release the cradle 55. This permits the overcenter springs 53 to actuate the operating mechanism and open the contacts as will be more fully described later.

The trip device is also operated magnetically to instantaneously trip the breaker on the occurrence of a heavy overload, for instance, 1000% or more of rated current or on short circuits in the circuit of any one of the poles.

For this purpose each pole of the breaker is provided with an electromagnet indicated generally at 86 and which includes a U-shaped stationary core 117 through which extends the conductor 35, the conductor being suitably insulated from the magnet core 117. The electromagnet is also provided with a hinged armature 123 having a projecting arm 124 which is adapted to engage a projection 141 on the trip bar 87 and rock said bar and the latch member 111 counterclockwise to trip the breaker when the electromagnet is energized by heavy overload or short circuit current flowing through the conductor 35. The armature 123 is biased to unattracted position by a spring 135.

A leaf spring 143 (Fig. 2) disposed in a recess in one of the barriers 42 is tensioned against a flat surface of the trip bar 87 to bias the trip bar to neutral position and to prevent accidental tripping of the breaker due to jars or shocks.

The circuit breaker mechanism is shown in Fig. 2 in the closed circuit position. When the trip bar 87 is rocked in unlatching direction in response to an overload current in the circuit of any one of the poles, the latch 111 disengages

the cradle 55 and permits the springs 53 to rotate the cradle in a clockwise direction about its pivot 56. At the start of this rotation of the cradle 55, the projection 68 engages the stud 66 on the toggle link 51 and starts the toggle 49-51 in the direction to cause it to collapse. Continued movement of the cradle 55 carries the center line of the toggle link 49 to the right of the line of action of the springs 53 which then act to complete the collapse of the toggle. This rocks the arms 27 and the tie bar 28 counterclockwise carrying the contact arms 25 therewith to open circuit position.

In the closed circuit position (Fig. 2) the line of action of the spring 77 is above the pivot 26 of the contact arm 25 and biases the contact arm 25 in a clockwise direction about its pivot 26 to provide contact pressure. When the arms 27 are rocked counterclockwise, as above described, a tail 145 on the member 79 strikes a projection 147 molded integral with the base 11, causing the member 79 to rock clockwise pivoting at its point of contact with the bracket 81 and rocking the contact arm 25 counterclockwise about its pivot 26 on the arms 27. This movement of the contact arm 25 is limited by a projection on said arm striking a pin 149 in the arms 27. The breaker is shown in its tripped open position in Fig. 3.

The result of the pivoted contact arm construction and of the action of the overcenter spring 77 is to effect a greater contact separation when the breaker is opened, and also a higher speed of operation of the contacts in both opening and closing. This decreases the possibility of restriking of the arc, and also eliminates re-arcng due to vibration of the contact arm since the action of the contact toggle opposes rebound of the moving contact.

It may be stated here that the greater separation of the contacts resulting from the action of the toggle 79-25 makes possible the use of circuit breakers of the type disclosed in circuits carrying substantially higher value currents than has heretofore been possible with the required degree of safety. This results in considerable economy of manufacture, since the same base and operating mechanism may be utilized for breakers having low capacity rating and high capacity rating by substituting the contact arm of the invention for the prior art contact arm where the movable contact is mounted directly on the switch arm.

Another important advantage of the present invention is that, due to the pivoted contact arm construction, a greater pressure is applied to the contacts and a wiping action between the contacts is effected as the contacts start to open. As the switch arm 27 starts to move the contact arm pivot 26 away from the base 11, the spring 77 rocks the contact arm 25 clockwise about its pivot maintaining the tip of the contact 21 in engagement with the stationary contact 17. At the same time the clockwise rotation of the contact arm 25 moves the line of action of the spring an additional distance above the pivot 26, thus increasing the pressure applied by the spring 77 to the contact and causes the tip of the contact 21 to wipe along the face of the stationary contact 17 during the initial opening movement.

In ordinary circuit breakers when the contacts wear, the result is a decrease in the pressure applied to the contacts due to the lengthening of the contact springs. Another important feature of the instant invention is the automatic appli-

cation of increased contact pressure as the contacts wear. Referring to Fig. 2, it is obvious that as the faces of the contacts 17 and 21 wear, the contact arm 25 is permitted to rock farther in a clockwise direction about its pivot 26 which moves the line of action of the spring 77 farther above the pivot 26 permitting the spring to apply increased pressure on the contacts.

Following each automatic opening of the breaker due to an operation of the trip device, it is necessary to reset the mechanism to an operative condition before the circuit breaker can be reclosed. To reset the mechanism the lever 47 is rotated from the position in which it appears in Fig. 3 to its extreme counterclockwise or open position. Movement of the lever 47 is transmitted to the cradle 55 by means of a hook projection 151 which engages a portion 153 of the cradle 55 and rocks the cradle counterclockwise therewith. As the cradle 55 is rotated, the latching end thereof passes the latch member 111 and engages a projection 155 on the trip bar 87 rocking said trip bar clockwise slightly past normal position. At this rotation of the trip bar the projection 115 thereon rocks the latch lever 93 counterclockwise compressing the spring 185 and reengaging the lever 93 with the latch 109. The latch member 111 now has assumed its normal latching position in the path of the cradle 55.

After the cradle 55 has been relatched, the contacts may be closed manually by moving the handle 63 clockwise to its closed circuit position. During this movement of the handle, the line of action of the overcenter springs 53 crosses to the right of the pivot axis 69 of the toggle link 49 causing the toggle 49-51 to move to the overcenter position rocking the arms 27 quickly clockwise to close the contacts. As the arms 27 carry the contact arm 25 toward the closed contact position, the arm 25 strikes a projection 157 on the base at a point to the left of the pivot 26 (Fig. 2), causing clockwise rotation of the arm 25 about its pivot 26 and moving the line of action of the spring 77 overcenter above the pivot 26. The effect of this action is to cause a very quick snap action to close the contacts and to provide a more stable contact pressure which prevents bouncing or chattering of the contacts upon closure.

In order to open the contacts manually, the operating lever 47 is moved counterclockwise about its pivot. This movement carries the line of action of the springs 53 to the left of the pivot axis 69 of the toggle link 49 and the force exerted by the springs 53 now biases the toggle 49-51 away from its overcenter position. Before the lever 47 reaches its extreme counterclockwise or open position, this force becomes sufficiently great to cause the toggle to collapse. Since the toggle link 51 is pivotally connected to the switch arms 27 for the center pole, the arms 27 for all of the poles are rotated in a counterclockwise direction, causing simultaneous opening of the contacts for all of the poles of the breaker. The contacts are closed manually in the previously described manner.

The circuit breaker is entirely trip free, that is, it operates automatically in response to an overload to open the contacts regardless of the position of the operating lever 47.

The arc extinguishers 19, there being one provided for each pole of the breaker, are of the spaced plate type, and comprise, generally, a stack of slotted plates of magnetic material positioned adjacent the paths of movement of the contacts 21. The presence of these plates causes

the arc resulting from the rupture of the circuit to be drawn in the direction toward the ends of the slots which results in the breaking up of the arc into a plurality of short arcs and causes said arcs to be cooled and extinguished.

Fig. 4 illustrates a modified form of the contact arm 25. In this figure, the parts are shown in closed circuit position by the full lines and in open position by the dot and dash lines. The contact arm 25 is provided with a hook projection 159 which, in the closed contact position, projects into an opening 161 in a plate 163 secured to the base 11 of the breaker. When the breaker is opened either automatically or manually and the arms 27 rock counterclockwise, the projection 159 engages the upper edge of the opening 161 causing the contact arm 25 to rock counterclockwise about its pivot 26. When this occurs, a spring 165 compressed between the bracket 81 and a shoulder on a rod 167 pivotally connected to the contact arm 25 by a pivot pin 169, is moved below the center line 26—169 and acts to complete the counterclockwise movement of the contact arm 25 about the pivot 26. The projection 159 moves free of the opening 161 permitting the arms 27 to carry the contact arm 25 to fully open position as indicated by dot and dash lines (Fig. 4).

When the switch arms 27 are rocked to close the contacts, as above described, the toggle formed by the rod 167 and the contact arm 25 remains in the position indicated by dot and dash lines (Fig. 4) until the contact arm strikes the top of the plate 163 which thereupon causes clockwise rotation of the contact arm 25 about its pivot 26. At this movement, the projection 159 reenters the opening 161 and the line of action of the spring 165 moves above the center line 26—169 causing the contacts to close with a snap action. In the closed position, the spring 165 applies pressure to the contacts 17—21.

The operation and advantages of this modification of the contact arm construction are the same as described in connection with the original embodiment. The construction of this modification provides greater contact separation, higher speed operation of the contacts, wiping action of the contacts, increased contact pressure during the initial opening movement and also when the contacts wear down, and prevents vibration or oscillation of the moving contacts, the same as in the original embodiment.

The remaining structure of the circuit breaker and its operation is the same as shown and described in connection with the original embodiment.

Certain features of the circuit breaker and trip device construction illustrated and described in this application are disclosed and claimed in our copending application for Circuit breaker, Serial No. 399,457, filed June 24, 1941, and assigned to the assignee of the present invention.

Having described several embodiments of the invention in accordance with the patent statutes, it is to be understood that various changes and modifications may be made in the structural details disclosed without departing from some of the essential features of the invention. It is, therefore, desired that the invention be interpreted as broadly as the prior art permits, and that it be limited only by what is expressly stated in the following claims.

We claim as our invention:

1. In a circuit breaker, the combination of relatively movable contacts including a station-

ary contact and a movable contact, a switch arm movable to open and close the contacts, actuating means for moving said switch arm, a contact arm pivotally mounted on the switch arm, said 5 movable contact being mounted on said contact arm, means cooperating with said contact arm to form a toggle disposed for movement with the switch arm, and means engageable by said toggle when the switch arm is moved to open the contacts to cause said toggle to move the contact arm about its pivot in an opening direction.

2. A circuit breaker comprising a stationary contact, a movable contact, a switch arm movable to open and close the contacts, actuating 15 means for moving the switch arm, a contact arm pivotally mounted on the switch arm, a toggle link cooperating with the contact arm to form a toggle disposed for movement with the switch arm, and a fixed member engageable by the toggle 20 when the switch arm is moved to open and to closed positions to cause the toggle to move the contact arm about its pivot to open and close the contacts with a snap action.

3. In a circuit breaker, the combination of 25 relatively movable contacts including a stationary contact and a movable contact, a pivoted switch arm movable to open and close the contacts, a contact arm pivotally mounted on said switch arm, the movable contact being secured on said contact arm, actuating means for moving the switch arm, a spring actuated member cooperating 30 with the contact arm to form a toggle mounted for movement with the switch arm, means engageable by said toggle when the switch arm is moved to open position to cause said toggle to move the contact arm about its pivot in an opening direction, and engageable by the toggle when the switch arm is moved to close the contacts to cause said toggle to move the contact arm about its pivot in a closing direction with a snap action.

4. A circuit breaker comprising relatively movable contacts, a movable switch arm, a contact arm pivotally mounted on said switch arm, said 45 contact arm having one of said contacts mounted thereon, operating mechanism for moving the switch arm to open and closed positions, means cooperating with the contact arm to form a toggle for moving the contact arm about its pivot, said toggle being movable with the switch arm, and means engageable by the toggle for causing 50 said toggle to move the contact arm about its pivot to open and closed positions when the switch arm is moved to open and closed positions.

5. A circuit breaker comprising a stationary contact and a movable contact, a switch arm movable to cause opening and closing of the contacts, operating mechanism for moving the 60 switch arm to open and closed positions, a contact arm pivotally mounted on the switch arm and having said movable contact mounted thereon, means cooperating with said contact arm to form a toggle movable with the switch arm for rotating the contact arm, means engageable by said toggle when the switch arm is moved to open position for moving the contact arm about its pivot in a direction away from the stationary contact, and other means engageable by the toggle when the switch arm approaches closed position for moving the contact arm about its pivot in a direction towards the stationary contact.

6. A circuit breaker comprising a stationary

contact, a pivotally mounted switch arm, a contact member pivotally supported on said switch arm and adapted to cooperate with the stationary contact, actuating means for rotating the switch arm about its pivot to open and close the contacts, a toggle member cooperating with the contact member to form a toggle, and means engageable by said toggle when the switch arm is rotated to open the contacts to move said toggle overcenter in a direction to cause movement of the contact member about its pivot in an opening direction.

7. In a circuit breaker, the combination of a stationary contact and a movable contact, a switch arm movable to open position and to closed position, actuating means for moving the switch arm to open and close the contacts, said contacts forming the sole means for interrupting the circuit, a contact arm pivotally mounted on the switch arm, a spring actuated toggle link cooperating with the contact arm to form a toggle, said toggle being disposed for movement with the switch arm, and means comprising an insulating member engageable by the toggle when the switch arm is moved to closed position to cause the toggle to move overcenter in a direction to close the contacts with a snap action, said toggle acting to apply pressure to the contacts when they are closed.

8. In a circuit breaker, the combination of a stationary contact and a movable contact, a switch arm movable to open and closed positions, a contact arm pivotally supported on the switch arm, actuating means for moving the switch arm to open and close the contacts, a spring actuated member cooperating with the contact arm to form a toggle movable with the switch arm, and means engageable by the toggle during the first part of the opening movement of the switch arm for moving the toggle overcenter in a direction to cause movement of the contact arm about its pivot in an opening direction with a snap action, said means being engageable by the toggle when the switch arm approaches closed position for moving the toggle overcenter in a direction to cause the contacts to close with a snap action.

9. In a circuit breaker, the combination of relatively movable contacts, a switch arm movable to open and closed positions, a contact arm pivotally mounted on the switch arm, actuating means including a toggle for moving the switch arm to open and close the contacts, an overcenter

5 spring operatively associated with the contact arm for actuating said contact arm about its pivot and a fixed member engageable by said contact arm upon movement of the switch arm to open and closed positions to initiate movement of the contact arm about its pivot in opening and closing directions respectively.

10. In a circuit breaker, the combination of relatively movable contacts, a pivoted switch member movable to open and closed positions, a contact arm pivotally supported on the switch member, actuating means for moving the switch member to open and close the contacts, and means cooperating with the contact arm to form a toggle, said toggle being engageable with a fixed member upon movement of the switch member to open and closed positions to actuate the contact arm about its pivot in opening and closing directions.

15 11. In a circuit breaker, the combination of relatively movable contacts, a switch member movable to open and close the contacts, a contact arm pivotally supported on the switch member, actuating means for the switch member, and a spring biased toggle link movable with the switch member and cooperating with the contact arm to form a toggle, said toggle during the first part of the opening movement of the switch member being effective to apply increased pressure to said contacts, and fixed means engageable by said toggle at a predetermined point in the opening movement of the switch member to initiate actuation of said contact arm about its pivot in opening direction.

20 12. A circuit breaker comprising a stationary contact, a pivoted switch member movable to open and to closed circuit position, a contact arm pivotally mounted on the free end of said switch member for cooperating with said stationary contact, means comprising a compression spring associated with said contact arm and said switch member for actuating said contact arm about its pivot, a guide link for supporting said spring pivotally engaged at one end with one end of said contact arm, a guide mounted on said switch member adjacent the pivoted end thereof for slidably supporting the other end of said guide link, said spring being disposed between said guide and a shoulder on said link.
